BOSS FORMING PROCESS

Thomas William Lowery, Detroit, Mich., assignor
to Chrysler Corporation, Highland Park, Mich.,
a corporation of Delaware

Application November 9, 1940, Serial No. 365,134

4 Claims. (Cl. 29—148)

This invention relates to an improved process of forming integral tubular bosses on plate or sheet metal.

It has heretofore been the practice to punch an aperture in a piece of plate or sheet metal before drawing the metal around the aperture thus formed into a cylindrical boss or short hollow tube of diverse cross section. The depth of draw has been limited by the occurrence of checks and cracks extending from edge portions of the metal severed during the punching operation and even in the production of shallow drawn bosses, such checking, splitting or cracking at this location has necessitated removal of considerable metal in order to trim the free end of the boss for commercial requirements.

One of the main objects of the invention is to so form the aperture in sheet or plate metal preparatory to the boss drawing operation as to guard against the occurrence of checks and cracks at the cut edges of the metal during the boss drawing operation.

Another object of the invention is the provision of an improved boss forming process of this kind by which a boss can be drawn to considerably greater lengths without the occurrence of checks and cracks at the free extremity of the boss.

Another object of the invention is the provision of an improved aperture forming step in a process of this kind which does not weaken or otherwise stress or distort the metal surrounding the aperture from which the free end part of a drawn boss is formed.

Another object of the invention is to provide for the removal of the metal surrounding a punched hole by cutting of increments of small depth therefrom in order to remove the depthwise punch scratches and strained metal without producing similar or other objectionable metal around the final aperture and in the portion of the stock to be drawn.

An additional object of the invention is the provision of an aperture forming step in a hollow drawn boss forming process which leaves only insignificantly deep tool marks which do not extend depthwise of the edge of the aperture but extend completely or partly circumferentially around the latter.

Illustrative embodiments of the invention are shown in the accompanying drawing, in which:

Fig. 1 is a side elevational view of an aperture forming tool showing the first step of the improved hollow boss forming process.

Fig. 2 is a view similar to Fig. 1 but showing the second step of the process.

Fig. 3 is a fragmentary sectional view illustrating another step of the improved process by which a hollow boss is drawn from a blank apertured as shown in Figs. 1 and 2.

Fig. 4 is a plan view of a blank provided with a punched aperture showing diagrammatically and on an enlarged scale, the effect of the punching operation upon the metal surrounding the aperture.

Fig. 5 is a plan view of a blank showing an aperture formed therein in accordance with the invention.

Fig. 6 is a perspective view of a metal plate having an integral boss formed in accordance with the invention.

Fig. 7 is a fragmentary side elevational view partly in section, of alternative apparatus which may be used to remove the metal disturbed by an aperture punching apparatus preparatory to drawing a tubular boss.

Fig. 8 is a fragmentary side elevational view, partly in section, of apparatus by which a punched aperture may be formed in an operation preceding that illustrated in Fig. 8.

25 In the form of the invention illustrated in Figs. 1 to 3 of the drawing, a hollow tubular boss is formed integral on a sheet or plate metal blank 10 by the following steps. The blank 10 is placed upon a supporting die 11 having an aperture 12

30 therein of somewhat larger diameter than the diameter of an aperture which is initially punched in the plate. The initial aperture is formed by a tool, generally designated by the numeral 13, having a body portion 14 and a punch member

35 15 provided on its leading end. The punch member 15 has a protruding pointed centering element 16. The intermediate portion of the body part of the tool 13 has spiral drill-like cutting blades 17 extending laterally beyond the maximum diameter of the punch member 15. Provided on the

40 opposite extremity of the body portion of the tool 13 is a shank 18 having flattened surfaces 19 by which the tool may be non-rotatably clamped in a chuck, press or similar device. During the initial operation the punch member 15 forms an undersized aperture in the blank 10 of smaller diameter than the passage 12 of the die 11.

The metal of the blank 10, as illustrated in Fig. 4, surrounding the initial punched aperture is 45 scored, checked or otherwise detrimentally effected by the punching operation. Generally, the scores or tool marks 20 left by the punch extend axially of the stroke of the punch or in the direction of the thickness of the blank. While these marks or scratches are frequently of only slight

depth, they so weaken the metal surrounding the initial punched aperture as to cause severe cracking around the free extremity of a tubular boss drawn from the metal of the blank bordering the aperture. In the practice of the present invention, all of the metal surrounding the initial punched aperture which has been so affected by the punching operation is removed without forming other tool marks extending depthwise of the aperture. This may be accomplished by merely drilling out the undersized aperture to the final desired diameter with a conventional metal drill. In such an operation any tool marks which remain extend circumferentially of the wall of the final aperture and do not cause cracking and checking during the boss drawing operation.

Substantially the same results may be obtained by broaching away the metal surrounding the initially punched aperture in the manner illustrated in Fig. 2. When this operation is conducted with a tool of the type shown in Figs. 1 and 2, the broaching step may follow the punching operation in rapid succession and after the punching member 15 has formed the initial aperture, the portion of the tool having the spiral cutting blades 17 thereon may be forced through the initial aperture during the same stroke of the tool in which the latter is punched. The portion of the tool on which the spiral cutting blades are formed may have a slight taper, from a minimum diameter at the end thereof adjacent the punch member 15 to a maximum diameter adjacent the shank end of the tool. The tool 13 may be held against rotation relative to the work during this step of the operation or it may be drivingly rotated in a drill-like manner.

If desired, the initial aperture may be formed by the conventional punch and die 21 and 22 illustrated in Fig. 8 and the metal surrounding the initially punched aperture may be removed by a conventional broach 23 as illustrated in Fig. 7. The broach 23 is preferably so constructed as to cut away successively small portions of metal in order to avoid formation of depthwise extending tool marks and scratches in the wall surrounding the final aperture.

After the initial aperture has been enlarged in any of the foregoing manners, its bounding wall 24, illustrated in Fig. 5, is substantially free from tool marks of sufficient depth to cause checking and cracking during the boss drawing operation. When the enlargement of the initially formed aperture is made by a drill or by a broach having spiral cutting blades, as illustrated in Figs. 1 and 2, any tool marks which remain extend circumferentially of the wall of the aperture or transversely of the depth of the latter.

When a blank pressed in this manner is subjected to a boss drawing operation such as that illustrated in Fig. 3 wherein a punch 25 presses the metal surrounding the aperture into a die 26, the extremity 27 of the resulting boss 28 does not crack or become serrated. Tubular bosses of substantially greater length may be formed from sheet or plate metal blanks prepared in the foregoing manner without requiring removal of excessive amounts of metal from the free ends of the bosses.

Although but several specific embodiments of the invention are herein shown and described, it will be understood that various changes in the

size, shape and arrangement of parts may be made without departing from the spirit of the invention.

I claim:

- 5 1. The process of forming a tubular boss on a flat portion of a sheet or plate metal blank which comprises forming an aperture in said flat portion having a bounding wall of undisturbed metal substantially free from depthwise extending shear lines and scratches by initially forming by a punch an undersized hole in said blank and subsequently enlarging said hole by cutting away successive portions of the metal surrounding the undersized hole along shear lines extending transversely of the thickness of said blank with spiral cutting elements provided on the lateral sides of said punch during continuation of the punching stroke thereof, and drawing the metal surrounding the resulting enlarged aperture to the form of a tubular boss.
- 10 2. The process of forming a tubular boss on a flat portion of a sheet or plate metal blank which comprises forming an aperture in said flat portion having a bounding wall of undisturbed metal substantially free from depthwise extending shear lines and scratches by initially forming by a punch an undersized hole in said blank and subsequently enlarging said hole by cutting away successive portions of the metal surrounding the undersized hole along shear lines extending transversely of the thickness of said blank with spiral cutting elements provided on the lateral sides of said punch by rotating the latter as a drill, and drawing the metal surrounding the resulting enlarged aperture to the form of a tubular boss.
- 15 3. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 20 4. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof along shear lines extending transversely of the thickness of said blank, and drawing the metal surrounding the resulting enlarged aperture in the direction of the axis of the latter to the form of a tubular boss.
- 25 5. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 30 6. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof along shear lines extending transversely of the thickness of said blank, and drawing the metal surrounding the resulting enlarged aperture in the direction of the axis of the latter to the form of a tubular boss.
- 35 7. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 40 8. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 45 9. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 50 10. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 55 11. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 60 12. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 65 13. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.
- 70 14. The process of forming a tubular boss on a sheet metal blank which comprises the steps of punching an undersized aperture in said blank preparatory to drawing the metal surrounding it to the form of a tubular boss and so as to admit access by a cutting tool to the metal which in the finished product comprises the free extremity of said boss, enlarging said aperture and simultaneously removing from the metal of the wall portion thereof punch formed scores and tool marks by progressively shearing from successive portions of the entire extent of said wall small increments of the metal thereof, and drawing the metal surrounding the resulting enlarged aperture in the direction of the axis of the latter to the form of a tubular boss.

THOMAS WILLIAM LOWERY.
